UNITED STATES PATENT OFFICE

WILBUR H. ARMACOST, OF NEW YORK, N. Y., ASSIGNOR TO THE SUPERHEATER COMPANY, OF NEW YORK, N. Y.

REHEATER

Application filed October 31, 1931. Serial No. 572,356.

The present invention relates to the art of heat exchange.

Heat exchangers for reheating steam and like purposes are in common use which have a shell through which the fluid to be heated passes and which have heating coils within the shell. Such heaters are compact and, when used as steam reheaters, avoid carrying large steam mains from the prime mover to the boiler furnace and back. Since, however, it is usually desired that the steam, or other fluid to be heated, make more than one pass in the heater, the shell of the ordinary form of such heater is subject to stresses caused by unequal thermal expansion due to the higher temperature of the fluid being heated in the outgoing pass over that in the incoming pass.

It is an object of my invention to provide an arrangement adapted to minimize stresses from thermal expansion.

A further object of my invention is to provide a novel form of coil unit for use in steam heated heat exchangers.

The novel features of my invention are pointed out in the appended claims. The invention itself, however, together with its objects and advantages, will best be understood from a detailed description of two forms of heat exchanger selected by way of example from a number of possible embodiments of the invention, and such a description will now be given in connection with the accompanying drawings in which—

Fig. 1 is a longitudinal sectional view, parts being broken away, of an apparatus within my invention.

Fig. 2 is a section taken on the line 2—2 of Fig. 2 looking in the direction of the arrows.

Fig. 3 is a longitudinal sectional view of a second form of heat exchanger within my invention.

Fig. 4 is a section taken on the line 4—4 of Fig. 3, looking in the direction of the arrows.

Fig. 5 is a detail of a portion of one of the heating units illustrated in Figs. 3 and 4.

Fig. 6 is a view similar to Fig. 5 but includ-

ing also a portion of the supports for the heating unit.

Fig. 7 is a view of a portion of a heating unit taken at right angles to Figs. 5 and 6.

Fig. 8 is a top view of a portion of the unit shown in Fig. 7.

The apparatus illustrated in Fig. 1 comprises a cylindrical shell 10 having an inlet 12 near its upper end for fluid to be heated and an outlet 14 for such fluid somewhat below inlet 12. In the arrangement shown, fluid passing inwardly through opening 12 enters a chamber 16 which is enclosed by the upper end or head 18 of the shell, the vertical wall 20 and horizontal plate 22 as well as a portion of the cylindrical wall of the shell 10. Fluid passes out of chamber 16 through an opening in the wall 20, a steam separator 24 of known type being placed on the opposite side of wall 20 from chamber 16 to act on fluid going therefrom.

Horizontal plate 22 extends across the bottom of chamber 16 and some distance beyond the wall 20 and forms the top of a central upper pass 26 within shell 10 which has a polygonal, preferably square, section, defined by walls 28, 28a. Pass 26 is open at the bottom to receive fluid to be heated which rises therethrough to the level of the outlet 14. Outlet 14, as clearly appears in Fig. 1, leads out of the upper end of pass 26. The separator 24 being near the top of shell 10 and the lower end of the pass 26 being near the lower end thereof, the ingoing relatively cool fluid from the outlet of separator 24 flows downwardly through the shell to enter pass 26. In order to avoid, as far as possible, unequal thermal expansion and the stresses produced thereby, it is desirable that the flow of fluid within shell 10 be as symmetrical as possible. For this purpose I have arranged that the relatively cool liquid contact the shell 10 around its entire cylindrical portion. In the arrangement shown for this purpose, the pass 26 has a cross section in the form of a polygon, preferably square, whose corners are internally in contact with the surface of shell 10 and lie parallel to the longitudinal axis of such shell. This arrangement is shown in dotted

lines in Fig. 2 and is better illustrated in Fig. 4, this feature being common to both the form illustrated in Figs. 1 and 2 and that illustrated in Figs. 3 and 4. By this arrangement, 5 the wall of pass 26 forms three similar longitudinal passages 30, 30 of similar segmental cross section, and a fourth segment 30' whose chord wall is shown at 28a. In the arrangement shown in Figs. 1 and 2 the fluid from 10 separator 24 can pass directly downward through one of the passages 30 lying opposite the inlet 14 and can pass around the top and ends of the separator 24 to the top of the passages 30 which have their plates 28 parallel 15 to the axis of outlet 14. The segmental passage 30a on the same side of the shell is closed by the plate 22 at the top, but is filled with steam or like fluid being heated which passes around the lower edges of the plates 28 and 20 28a and which is of substantially the same temperature as that in passages 30.

Elements for heating the fluid in pass 26 are shown at 34. Steam, or like heating fluid, for elements 34 may be introduced into the 25 shell 10 through the header 32 which has heating elements 34 connected thereto in any known or preferred manner. The heating elements 34 extend up into the pass 26 and heat the fluid which passes therethrough in 30 contact with the exterior of the elements in the usual manner. Elements 34 may have their other ends connected to a discharge header (not shown) similar to header 32 or they may be so arranged that the condensate will drain 35 back through header 32.

In the arrangement illustrated in Figs. 3 and 4 the cylindrical shell 10a has a partition 28b therein arranged to form an up-pass 26a having a polygonal cross section. As illustrated, partition 28b is arranged to give the pass 26a a square cross section, the transverse cross section of the partition forming a square circumscribed within shell 10a and whose corners are welded or otherwise secured thereto 40 along lines parallel to the axis of the shell. Partition 28b therefore forms, together with the shell 10a, chambers of segmental cross section extending longitudinally of the shell 10a on the outside of the partition 28b. Two of 45 such segments are designated in Figs. 3 and 4 by reference character 30a, 30a and two other such segments are designated by reference character 30b, 30b. The upper end of pass 26a is open so that fluid may pass around 50 the upper edge of the partition 28b into the chambers 30a which are used together as a down-pass. Fluid to be heated is introduced into the heat exchanger shown in Figs. 3 and 4 thru inlet 12a which passes thru shell 10a 55 and delivers into the up-pass 26a thru partition 28b. The fluid to be heated thereupon travels up thru the pass 26a and down thru 60 passages 30a and discharges from the shell thru the outlet 14a, which is preferably about 65 on the same level as the inlet 12a, both inlet

and outlet being near the one end of the shell 10a. Fluid which has been heated and which passes down thru the segmental chamber 30a on the side of the outlet 14a can pass directly 70 into such outlet while fluid passing down thru chamber 30a on the side of the inlet 12a can pass between the lower end of the pass 26a and the end or head 18 of the shell and thence somewhat upwardly thru the lower end of the other passage 30a and into the outlet 14a. As 75 shown, pass 26a is closed at its bottom by plate 64 to form a passage 31 to connect the chambers 30a in the manner just described. The segmental chambers 30b are closed at their lower ends by plates (not shown).

The fluid which enters the heat exchanger of Figs. 3 and 4 thru inlet 12a is heated in pass 26a by a tube bundle T. Bundle T is composed of units one of which is illustrated in part in Figs. 5 and 6, each unit having two 80 elements 34a therein, parts of which are of serpentine form, portions of the serpentine parts of one such element being shown on an enlarged scale in Figs. 7 and 8. Heating fluid such as steam or the like for bundle T is introduced thru shell 10a by an inlet header 32a. Each element 34a has an inlet section 34b which is connected so as to receive heating fluid from header 32a. Each element 34a also has an outlet section 34c connected to deliver fluid to an outlet header 33a whereby used heating fluid is discharged 85 thru the shell 10a. The elements 34a are bifurcated at the points 70, 71 near their tops and bottoms respectively. The sections 34b and 34c between the headers and points 70 and 71 respectively have equal diameters and are sufficiently larger than the individual pipes used intermediate points 70 and 71 so that the inlet sections 34b and outlet sections 90 34c have approximately twice as much cross sections as the individual pipes of the elements intermediate such points, each element having, however, the same total cross sectional area throughout. The bifurcated 95 portions of elements 34a, which are also the parts of serpentine form, consist of straight pipe runs 60a connected by return bends some of which are of the welded type, as 100 shown at 58, while others are of the plain type, as indicated at 66 and 67. The inlet sections or portions 34b extend upwardly along the partition 28b to the top of bundle T and the serpentine portions of the elements thereupon conduct the heating fluid downwardly to the outlet portion 34c. Elements 105 34a have a form which minimizes the number of welded bends 58 and utilizes fully the polygonal or square section of pass 26a so as to provide a large ratio of heating surface 110 to volume in a pass of square cross section. As appears more clearly in Fig. 7, the runs 115 60a of the bifurcated tubes are inclined to the horizontal and are bent back and forth in the horizontal and vertical directions. Along 120 125 130

one end of the given serpentine part, bends 66, 66 curve in the horizontal direction and the two parts of a given bifurcated tube lie one above the other, whereas at the other end 5 of the serpentine the bends 58 and 67 lie in the same vertical plane, the two parts of the bifurcated tube of a given element being arranged so that the bends 58 and 67 come one within the other. As shown, the inner bend 10 58 of such a pair is formed advantageously by welding the ends of adjacent tube runs 60a.

The arrangement of the serpentine portions of two elements 34a to form a unit for 15 insertion and removal in shell 10a is best illustrated in Figs. 5 and 6. It will be clear from these figures that two pairs of hangers 48a and two beams 44a are combined with two elements 34a to form a unit for suspension in the pass 26a.

Also, as appears clearly in Figs. 3 and 4, the two tube elements of each unit are placed 20 face to face and interleaved so that one series of vertical bends 58 and 67 of each element lies within the horizontal bends 66 of the other element of the same unit.

As appears clearly in Figs. 3 and 4, the inlet sections 34b of each element 34a preferably run upwardly close to the partition 28b. 25 As further appears from Fig. 4, some of sections 34b are on the side of pass 26a adjacent one passage 30a and some on the side of the pass adjacent the other passage 30a. The section of the partition 28b between the up 30 and down pass is thereby heated, and interchange of heat between the incoming and outgoing streams of fluid is thereby prevented. I prefer to use heating elements of 35 the type illustrated in Figs. 3 and 4 in the apparatus of Figs. 1 and 2, but do not limit myself to this.

In the arrangement shown in Figs. 3 and 4 as well as in Figs. 1 and 2, the ends of shell 40 10a are closed by heads within which are manholes 68.

It will be seen that in Figs. 1 and 2, chambers 30 have substantially the same temperature throughout their lengths when in use and that the portions of the shell 10 covering such 45 chambers are at substantially the same temperatures as the corresponding chord portions of partition 28, so that there is a minimum of thermally produced distortion and stress.

50 The chamber 30', while having no flow therein, receives heat from the steam in pass 26 so that its shell portion and partition portion soon reach and maintain the same temperatures at given levels whereby the thermal 55 stresses are minimized.

Similarly as to the arrangement of Figs. 3 and 4, the wall portions of chamber 30a are all at substantially the same temperature throughout while in use and the wall portions 60 65 of chambers 30b, while not entirely at

uniform temperatures, have their temperature differences so distributed that the temperatures are the same at given levels and the stresses thereby minimized.

What I claim is:

1. A heat exchanger having a shell, walls within said shell forming a pass for fluid to be heated and which has a polygonal cross section, said walls forming segments within said shell and the walls and shell having an arrangement such that the fluid in certain of said segments maintains the metal walls thereof at substantially the same temperature at given levels within the segment, heating elements within said polygonal pass, said segments each having communication with said polygonal pass at one end, and an inlet and an outlet connection, one to said polygonal pass and one to one of said segments.

2. The heat exchanger as set forth in claim 1 and in which the inlet and outlet are substantially at the same level.

3. A heat exchanger having a cylindrical shell and walls therein forming a central pass of polygonal cross section the corners of which are parallel to the axis of said shell and secured thereto to form chambers of segmental cross section which connect with said polygonal pass and some of which are utilized as a second pass.

4. A heat exchanger having a cylindrical shell and walls therein forming a pass of rectangular cross section, a tube bundle for heating fluid in said pass and having elements, each comprising inlet sections and outlet sections connected by bifurcated serpentine sections, some of said inlet sections extending along one side and some along the opposite side of said rectangular pass and said inlet and outlet sections entering said pass at the same end.

5. A coil element for heat exchangers having means at its ends for connection to headers, and an intermediate serpentine portion comprising parallel tubes having a series of coplanar reverse curves and a series of reverse curves in planes substantially at right angles to said coplanar curves.

6. A coil element for heat exchangers having means at its ends for connection to headers, and an intermediate serpentine portion comprising two parallel tubes having a series of coplanar reverse curves and a series of reverse curves in planes substantially at right angles to the plane of said coplanar curves, the inner ones of the coplanar curves comprising welded ends of adjacent tube runs.

7. A unit for heat exchangers comprising two elements each of which has means at its ends for connection to headers, and an intermediate serpentine portion comprising parallel tubes having a series of coplanar reverse curves and a series of reverse curves in planes substantially at right angles to said coplanar

curves, the unit having the two elements interleaved so that the coplanar curves of one are embraced by non-coplanar curves of the other element.

5. A heat exchanger as set forth in claim 4 and in which the two segmental chambers between the rectangular pass and the shell of the exchanger which are on the same sides of said pass as the inlet and outlet sections 10 of the elements have connections with said rectangular pass at one end, and a connection with the exterior of the shell whereby they form a second pass.

6. A heat exchanger having a vertical shell, an inlet chamber within the upper end of said shell, a down-pass along the shell, an up-pass substantially central of said shell and connected to said down-pass, and an outlet connected to the upper end of said up-pass for discharging heated fluid through the shell.

7. A heat exchanger as set forth in claim 9 and in which a separator is arranged to act on steam intermediate the inlet chamber and 25 the down-pass.
